STROLLER

John A. Conti, Dothan, Ala., assignor to Hedstrom Union
Company, Fitchburg, Mass.

Filed Mar. 6, 1963, Ser. No. 73,838

Term of patent 7 years

(Cl. D14—14)

FIG. 1

FIG. 3

FIG. 1 is a side view in perspective of a stroller embodying my new design;

FIG. 2 is an enlarged fragmentary side elevational view thereof; and

FIG. 3 is a fragmentary perspective view taken from the upper front.

The dominant features of my design reside in the portions shown in full lines.

I claim:

The ornamental design for a stroller, substantially as shown and described.
